(57) **CLAIM**

The ornamental design for a shower rod with end caps, as shown and described.

DESCRIPTION

FIG. 1 is a top perspective view of a shower rod with end caps in accordance with a first preferred embodiment of my design;

FIG. 2 is a top plan view thereof;

FIG. 3 is a bottom plan view thereof;

FIG. 4 is a front elevational view thereof;

FIG. 5 is a rear elevation view thereof;

FIG. 6 is a left side elevational view thereof; and,

FIG. 7 is a right side elevational view thereof.

The broken line showing of a back plate is included for the purpose of illustrating environmental structure and forms no part of the claimed design.

1 Claim, 3 Drawing Sheets

FIG. 4

FIG. 5

FIG. 6

FIG. 7
